UNITED STATES PATENT OFFICE.

LAURENCE M. OAKLEY, OF TRENTON, NEW JERSEY, ASSIGNOR TO CLIFFORD H. OAKLEY, OF TRENTON, NEW JERSEY.

RESILIENT HEEL LIFT.

Application filed February 5, 1920. Serial No. 356,374.

To all whom it may concern:

Be it known that I, LAURENCE M. OAKLEY, a citizen of the United States, and a resident of Trenton, in the county of Mercer and State of New Jersey, have invented an Improvement in Resilient Heel Lifts, of which the following is a specification.

The present invention relates to improvements in resilient heel lifts for attachment 10 to the heels of boots and shoes.

Among other objects the invention aims to provide a resilient lift so formed that its edges will be maintained, partly by the resiliency of the lift material, in close contact with the edges of a heel to which it may be applied. Further objects of the invention will be in part obvious from and in part pointed out in the following specification. It will be observed that the structure of the lift is such that it closely resembles a flat heel lift and is clearly a lift of the flat type.

A preferred embodiment of the invention has been selected for purposes of illustration 25 and description, but it will be understood that the invention is not limited thereto. In the accompanying drawings,

Figure 1 is a top plan view of an illustrative resilient heel lift embodying the invention;

Figure 2 is a longitudinal section on the line 2—2 of Figure 1;

Figure 3 is a longitudinal section on the line 3—3 of Figure 1;

Figure 4 is a cross section of the line 4—4 of Figure 1;

Figure 5 is a bottom plan view of the heel shown in Figure 1; and

Figures 6 and 7 are respectively longitudinal and cross sections of the heel lift of Figure 1 attached to the heel of a shoe, the respective planes of these sections being indicated by the lines 6—6 and 7—7 in Figure 5.

Referring to the drawings it will be observed that the illustrative heel lift is of substantially uniform thickness throughout. Such lifts are usually made of rubber or a rubber composition. The lift is formed on 50 its upper or attaching face, with a central plane portion or core 10 bounded on one side by the forward or breast edge 11. Extending from the breast edge near one corner, around the central core, and back

again to the breast edge near the other corner, is a groove or depression 12. The side edges 13 and the rear edge 14 are in substantially the same plane as the surface of the central core 10. As the lift is of substantially uniform thickness throughout the bottom or tread surface of the heel shows a central plane portion 15 corresponding in outline to the core 10 and surrounded by a continuous ridge 16 which extends from the breast edge around the central plane portion 15 and back to the breast edge.

One or more nail holes 17 may be formed in the central plane portion of the heel and in accordance with the usual practice corresponding washers 18 are imbedded in the rubber concentrically with the nail holes. In the grooved and rigid marginal portion of the heel a suitable number of nail holes 19, herein five in number, are formed and corresponding washers 20 imbedded in the rubber. Preferably these nail holes are located at the point of maximum displacement from the plane of the central core 10, along the median line of the groove. In the present instance, due to the regular curvature of the groove, the nail holes are located midway between the edges of the groove. It should be noted that the present construction permits of the nail holes being placed perpendicularly to the plane of the lift surface which, when attached is the plane of the shoe heel. The nails are, therefore, more easily driven without bending and without distorting the rubber adjacent the nail holes.

The heel lift just described possesses certain pronounced advantages over heel lifts of the prior art designed to secure intimate contact between the edge of the lift and the edge of the shoe heel without the use of cement. Such lifts, which are often referred to as concavo-convex, are deformable over substantially their entire area. This necessitates the location of the nail holes near the center of the heel, thus causing the intimate contact between heel lift and shoe heel to depend principally upon the continued resiliency of the material of the lift. In the present construction the nail holes may be located nearer the edge of the lift and, therefore, not only the resiliency of the lift material but the nails themselves, tend to produce a tight and intimate contact between

the edge of the heel lift and the edge of the shoe heel.

By restricting the deformable part of the heel lift, as in the present instance, there is provided a short arch from the outer edge of the central plane portion or core 10 to the edges 13 and 14 of the lift. The force necessary to deform the rubber in such a construction will be greater than in a construction which involves deforming the lift over a greater length. The opposed tendency of the rubber to resume its normal shape will be correspondingly greater and this will produce a greater pressure upon the edge of the shoe heel. The location of the nail holes near the edge is particularly advantageous in preventing a pulling away of the lift from the heel, when the wearer of such a lift strikes it against any object. Carrying the grooves 12 forward to the breast edge of the heel continues the edge gripping tendency of the heel uniformly to the breast corners which are most likely to be caught by the wearer and, if insecurely held, pulled away from the shoe heel.

It will be noted that the heel lift of the present invention possesses distinguishing characteristics of a flat heel which, although they may be of slight importance after the heel lift has been attached to a shoe, are of great importance in the handling and during the attachment of the lift. It will be noted a pair of lifts may be packed in the usual cartons and handled as flat heel lifts are handled. In attaching the lift of the present invention to a shoe heel it may be accurately centered thereon and the first nails driven through the central plane portion of the lift without in any way deforming the heel. Thus the possibility of the lift slipping or becoming misplaced during the initial nailing is minimized. This is due to the central plane portion of substantial area coming into immediate contact with the shoe heel when the lift is laid thereon. After the first fastening, nails have been driven through the lift, nails may be driven through the marginal portion of the lift to deform that portion and bring the upper side and rear edges of the lift into pressing contact with the shoe heel. If desired, the nails, which are at all times disposed perpendicularly to the shoe heel, may be driven simultaneously, as by an automatic nailing machine.

It will be understood that the illustrative embodiment of the invention above described may be variously modified within the scope of the subjoined claims.

I claim as my invention:

1. A deformable resilient heel lift of uniform thickness throughout, the upper surface of said lift having a central flat portion of a width equal to approximately one-third of the width of the lift and of substantial area disposed in a plane passing through the outer edges of the lift and a groove of uniform width throughout substantially its entire length; terminating at the breast edge of the lift and extending around said flat portion; the tread surface of the lift having a corresponding flat portion and a ridge of uniform width throughout substantially its entire length terminating at the breast edge and extending around said flat portion; the said lift being provided with nail holes positioned in said central flat portion and along the median line of said ridge and groove and disposed at right angles to the plane of said flat portion, whereby the lift when attached to a shoe heel may be deformed to produce a substantially uniform pressing contact from one breast corner along the side and rear edges of the heel to the other breast corner.

2. A deformable resilient heel lift having its upper surface formed with a central flat portion of substantial area and separated from the side and rear edges of the lift by a groove of substantially uniform width ending at the breast edge of the lift, and having its tread surface formed with a corresponding flat portion separated from the side and rear edges of the lift by a ridge, and nail holes disposed in said central plane portion and said ridge, the groove and ridge forming a deformed portion of substantially uniform width around the outer edge of the lift.

3. A heel lift of resilient material of substantially uniform thickness throughout and having an elongated central flat portion of a width equal to approximately one-third of the width of the lift upon its upper surface with a surrounding groove of substantially uniform width, one edge of said flat portion and the ends of said groove terminating flush with the breast edge of the lift, and fastening means passing through the lift along substantially the center line of said groove and adapted to deform the grooved periphery of the lift to hold the edges of the lift firmly against a heel.

In testimony whereof, I have signed my name to this specification this third day of February 1920.

LAURENCE M. OAKLEY.
